ORE ROASTING FURNACE

Paul Gates, 2675 Fashion Ave., Long Beach, Calif.

Filed July 15, 1957, Ser. No. 672,033

3 Claims. (Cl. 266—20)

This invention relates to an apparatus for the treatment of certain classes of ore and more particularly to the treatment of ore for extracting materials therefrom that volatilize and that may be precipitated in a condenser after volatilization.

In the treatment and extraction of ores, coal and other comminuted materials and products, considerable difficulty is encountered due to the volatile nature of the material being extracted from the ore. For example, the recovery of mercury from cinnabar, which is the principal ore in which mercury is found, involves many difficulties due to the volatile nature of the mercury and its chemical characteristics when in the vapor state. In the state of the art prior to the present invention, adequate control of the atmosphere in which the mercury ore is being heated has not been possible in any apparatus which furnishes a continuous cycle of ore treatment and extraction. That is, if ore is charged to, and the mercury and residue removed from the furnace, while the furnace is in operation, the atmosphere within the extraction furnace is substantially open since the ingress of air will occur during any continuous charging operation heretofore known to the art. Also the continuously charged furnaces of the prior art have been inefficient with respect to the heat input required since the large volume of air which is introduced into the furnace must be heated and is subsequently exhausted with a high heat loss. Heating inefficiency is also caused when a large quantity of ore is charged into a furnace and remains in a stationary condition during the heating operation, since a large mass must be present and is in effect baked, such that the outer layers of ore in the mass act as a partial insulator to the mass of ore within the center of the charge.

Accordingly, it is an object of the present invention to provide an improved ore furnace which allows the charging and extraction of ore from the furnace during operation of the furnace while controlling the atmosphere within the furnace.

It is another object of the present invention to provide an improved ore furnace which is compact, but provides an extensive ore heating surface while requiring a substantially smaller heat input than ore wasting furnaces heretofore known to the art.

It is another object of the present invention to provide an ore roasting furnace which subjects the ore within the furnace to an efficient heating cycle.

It is a further object of the present invention to provide an ore charging apparatus by means of which ore can be fed to a furnace heating chamber during operation of the furnace without a resulting ingress of air to the chamber.

A further object of the present invention is to provide an ore roasting chamber which causes agitated flow of ore through the furnace chamber.

A still further object of the present invention is to provide an ore roasting furnace in which a controlled atmosphere can be maintained in the heating chamber

2

by the addition of controlled amounts of air or other gases.

Yet another object of the present invention is to provide an ore roasting furnace in which the volatile constituents of the ore are driven off in a gaseous condition and condensed and recovered while in a controlled atmospheric condition.

A still further object of the present invention is to provide an ore roasting furnace in which a stream of ore is introduced to the furnace and conducted through the furnace while being heated and agitated to cause its volatile constituents to be liberated.

Yet another object of the present invention is to provide an ore roasting furnace having a high degree of heating and mechanical efficiency with a minimum of parts which are subjected to abrasive wear and containing no moving parts within the furnace chamber.

A furnace in accordance with the present invention comprises a shell defining a furnace heating chamber 20 with a plurality of ore carrying decks upon which the ore is moved from an ore inlet to an ore residue outlet along a tortuous agitated path. Means are provided for imparting an oscillatory movement to the ore carrying decks while a source of heat heats the ore to extract volatile materials during the tortuous movement. Ore inlet means and ore residue outlet means are provided which allow the charging of ore and extraction of ore residue during operation of the furnace without the ingress of air to the chamber or egress of gas or volatile constituents from the chamber. Air or gas inlet means allow control of the atmosphere within the chamber.

The novel features which are believed to be characteristic of the invention both as to its organization and method of operation together with further objects and advantages thereof will be better understood from the following description considered in connection with the accompanying drawing in which the invention is illustrated by way of example. It is to be expressly understood, however, that the drawing is for the purpose of illustration and description only and is not intended as a definition of the limits of the invention.

Figure 1 is a view in elevation and partly in section of a presently preferred embodiment of this invention as applied to a mercury ore furnace;

Figure 2 is a view in elevation taken along line 2—2 of Figure 1;

Figure 3 is a view of an ore travel deck taken along line 3—3 of Figure 1;

Figure 4 is a view corresponding to Figure 3 of an ore travel deck taken along line 4—4 of Figure 1;

Figure 5 is a view of the lowermost ore travel deck taken along line 5—5 of Figure 1;

Figure 6 is a partial view of the bearing support means taken along line 6—6 of Figure 1;

Figure 7 is a schematic view in perspective of the arrangement of the ore travel decks within the furnace chamber;

Figure 8 is a partial view in detail of the ore outlet means taken along line 8—8 of Figure 1;

Figure 9 is a partial view taken along line 9—9 of Figure 2; and

Figure 10 is a partially diagrammatic view showing the operation of the ore charging means at various operational stages of the furnace.

Referring now to the drawings the present invention will be described in connection with a presently preferred embodiment of a furnace used in the extraction of mercury from cinnabar. It is to be understood, however, that a furnace in accordance with this invention may be used for the extraction of other volatile materials from ore or shale, such as, for example, the extraction of oil from oil shale, and may also be used for such

operations as calcining, roasting, chloridizing, volatilizing, sintering, modulizing, drying operations and the like.

Referring now particularly to Figures 1 and 2 the furnace includes a shell 20 which is preferably heat insulated although such insulation is not shown for purposes of clarity in the drawings. The shell 20 is substantially rectangular in cross-section and is formed of any suitable material, such as high temperature resistant steel. Any means known to the art may be used to join the end plates 21 and 22, the side plate 23 and 24, and the top and bottom plates 25 and 26 respectively, so long as all joints are substantially gas tight to maintain the shell substantially hermetically sealed. The shell 20 is mounted for oscillatory movement by means of shafts 28 and 29 which are affixed to the first end plate 21 and the second end plate 22 respectively substantially on the longitudinal centerline of the shell. The shafts are mounted in rotary bearings 31, 32 which are in turn slidably mounted in brackets 33 and 34 for some vertical movement as shown in Figure 6. That is, the bearings are mounted in vertical grooves in the brackets 33 and 34 to allow some vertical movement of the shafts 28 and 29 due to expansion and contraction of the shell when it is heated or cooled. The brackets 33 and 34 are an integral part of, or are affixed to, support arms 35, which are in turn affixed to a suitable base 36 or the floor to maintain the shell at the proper height above the base. The shell is also supported at the end plates thereof by idler wheels 37 and 38 which are mounted for rotating movement by means of mounting brackets 41 and 42 affixed to the base 36. The idlers define a peripheral groove in which arcuate support members 43 and 44 respectively are mateable. The arcuate support members are concentric in configuration to the longitudinal centerline through the shafts 28 and 29 such that the shell is supported on the idlers by the arcuate members throughout oscillatory travel of the shell.

A bearing rod 46 and 47 is affixed to each end plate for connection of a driving arm 48 and 49, and the driving arms are in turn connected to a crank 50 which is supported and mounted from the base 36 for rotary movement. Suitable gearing and connections are made to a prime mover, not shown, by means well known to the art to drive the crank 50 through a full circular driving movement as shown. Although driving arms are shown connected to each end of the shell for purposes of symmetry, only one is essential and the means for connecting and driving the shell through an oscillatory movement are not critical and may be performed by any one of many means known to the art. In addition, it is not essential that the center of oscillation of the shell be on the longitudinal centerline of the shell, although it is preferable that the shell be mounted and driven such that it oscillates equally to both sides of the vertical plane as will become more apparent hereinafter. The angle through which the shell oscillates with respect to the vertical may be varied by adjusting the radius through which the driving arm 48 is rotated by the crank 50, and accordingly adjusting the length of the travel arm. The prime mover may be varied in speed to vary the speed of oscillation of the shell.

Within the shell 20 a plurality of ore carrying inclined decks are positioned. The decks 52 extend across the width and length of the shell and are affixed at the sides and ends of the shell. The decks are alternately inclined longitudinally with respect to the horizontal by an angle which is less than that at which the ore will slide due to its own weight. That is, the first deck 53 is inclined downward from left to right in the figures by an angle of two degrees with the horizontal, for example. The second deck 54 is also inclined at the same angle, but is inclined downward from right to left, while the third deck 55 is substantially parallel to the first deck 53 and is inclined downward from left to right at two degrees. Thus, the decks 52 are alternately inclined longitudinally, but

are not inclined transversely. At the lowermost end of the first and second decks an ore opening 57 and a fumes and heat opening 58 are provided as shown in Figures 1, 3, 4 and 7. The ore opening is positioned at one lower corner of the deck and is of sufficient size that ore may drop freely therethrough to the next lower deck. Thus, ore will progress as more fully described herein-after to the lower end of the first deck 53 and thence through the ore opening 57 to the upper end of the second deck 54. The openings 58 allow the passage of volatile constituents upward past successive decks and also allow the free circulation of heat upward within the chamber. From the lower end of the second deck the ore will drop to the third deck. Although three decks are shown in the presently preferred embodiment any number may be used dependent upon the length of passage through the furnace which is required in any given application of the present invention. A fumes and heat opening is provided through each deck as shown in the figures. In this embodiment the opening 58 is positioned at the lower corner of the deck opposite to the ore opening 57. In order to prevent ore from dropping through the opening 58 a side wall or shield 59 is affixed to the deck to block the movement of ore to the opening 58, thereby requiring the ore to travel the tortuous path and maintaining free openings for the travel of volatile constituents. The height of the shield is substantially greater than the thickness of ore moving along the deck, but is low enough not to interfere with the circulation of heat and fumes as described hereinafter.

The lowermost deck, referring particularly to Figures 1, 5 and 7, which is the third deck 55 in this embodiment, is coextensive with an ore outlet from the shell. That is, a heat opening 59 is provided at each of the lower corners of the third deck and shields 60 are affixed at the edge of the openings 59 to prevent entry of ore through the openings and to guide the ore to the core outlet opening 61 through the end plate 22 of the shell 20. Affixed to the end plate 22 surrounding the ore outlet opening 61 is an ore outlet chute 62 having a bottom plate 63 which is coextensive with, and continues the slope of the third deck 55 to provide an uninterrupted travel surface for the ore. The outlet chute 62 is closed and substantially gas-tight, and is affixed to the shell by means well known to the art to provide substantially gas-tight joints. At the outer end of the ore outlet chute 62 a substantially vertical tube 65 is provided in uninterrupted communication with the chute 62 to continue a closed ore passage from the chute as shown in Figures 1 and 8. A transparent plate 66 is inserted in the tube at the upper end thereof to furnish a view port. An air or gas inlet valve 67 is affixed to the tube 65 approximate the upper end thereof to furnish a means for introducing a controlled quantity of air or gas to the shell. In addition, the inlet valve 67 can be utilized to furnish auxiliary fuel such as butane, for example, to the chamber. The valve is of the type well known to the art and is of sufficient size to furnish the required volume of air flow for any given application. Suitable fittings can be affixed to the valve for the connection of a closed gas line.

At the lower end of the ore outlet tube 65 a controlled outlet means releases ore from the tube at a controlled rate such that some ore remains in the tube behind the outlet for a considerable vertical distance. In the presently preferred embodiment ore, or ore tailings, is restrained in the tube 65 for a predetermined distance, but allowed to escape therefrom by a spring-loaded plate 70 which is mounted a short distance beneath the open end of the tube. The plate 70 has side walls extending upward adjacent two opposed sides of the tube 65 and is open at the other two sides. The open sides of the plate are those which are parallel to the direction of oscillation of the tube 65 and shell 20. That is, in this embodiment, the plate has a U-shaped cross-section with the sides of the U positioned adjacent the walls of the tube

which are perpendicular to the direction of motion, and the base of the U positioned a substantial distance beneath the open end of the tube. The plate is spring mounted and is supported by a plurality of springs 71 in compression which are in turn mounted upon an adjustable platform 72. The platform 72 is adjustably fixed to the tube 65 beneath the plate 70 by means of support bolts 73 which are threadably connected to the tube 65 through bracket 74 such that the distance at which the platform is positioned beneath the plate can be varied to vary the spring pressure urging the plate toward the open end of the tube 65. Thus, it may be seen that ore, or ore tailings in the tube 65 will escape from the open sides of the plate 70, but that the upward force of the plate will restrain the flow of ore sufficiently to cause a substantial quantity of ore to be retained in the tube. As the shell and tube oscillate, the weight of ore acting to compress the springs 71 will vary to agitate the ore within the tube. Thus, the plate 70 allows escape of ore residue from the tube while maintaining ore residue in the tube to a predetermined height to prevent the ingress of air through the tube as discussed more fully hereinafter.

At the top of the shell 20 an ore charging means is provided to allow the charging of ore to the shell while preventing the ingress of air to the shell. Referring particularly to Figures 1, 2 and 10, the ore charging means includes an ore inlet tube 75 which extends through the top plate 25 of the shell 20 in substantially gas-tight contact therewith. The ore inlet tube is positioned approximate the upper end of the first deck 53 to deposit ore thereon. The ore inlet tube 75 has an open lower end and extends into the interior of the shell, i.e., to a substantial distance beneath the top plate 25. Positioned a short distance beneath the open end of the tube 75 is an ore inlet plate 76 which is adjustably affixed to the top plate 25 by means of bolts 77 which are threadably connected to the top plate to vary the distance of the ore inlet plate 76 beneath the open end of the tube 75. The ore plate in this embodiment is again substantially U-shaped in configuration with the sides of the U positioned adjacent the sides of the rectangular inlet tube 75 which are perpendicular to the direction of oscillation of the shell, to provide ore outlets from the tube which are perpendicular to the direction of oscillation and variable in size. A flow of ore to the inlet tube 75 is obtained without an opening to the atmosphere which would allow ingress of air or escape of gas or volatile constituents of the ore which are driven off. The upper end of the ore inlet tube is coextensive with branches 78 and 79 respectively which are connected with the inlet tube 75 and disposed to opposite sides of the center line of the tube at an angle substantially equal to or greater than the maximum angle of oscillation of the shell. The ore passage branches 78, 79 are connected with an arcuate trough 80 at opposite ends thereof. Thus, in this embodiment the ore inlet trough 80 has a radius of curvature which is substantially symmetrical with the center of oscillation of the shell 20, and the ends of the trough connect with branches 78 and 79 which in turn are joined at the ore inlet tube 75.

Thus, referring particularly to Figure 10, it may be seen that at or near one extreme of oscillation of the shell 20 and the attached charging trough 80, the sleeve 82 will be in register with a branch 78 and ore may flow from the hopper to the branch 78 and thus downward to the tube 75. During the oscillatory cycle the bottom plate of the arcuate trough 80 passes beneath the sleeve 82 in sliding contact therewith and prevents flow of ore toward the ore inlet tube 75, until registration with the other branch 79 is obtained at or near the opposite extreme of oscillation. The divided position of the branches 78 and 79 with respect to the oscillatory cycle prevents overflow of ore from the branches or the buildup of ore ahead of the sleeve 82. Flow of ore is thus controlled and ingress of air or egress of fumes or volatilized

material is prevented as discussed hereinafter in connection with the description of operation.

As shown in Figures 2 and 9, an impact means is provided at the ore inlet which comprises a ball 84 confined within a track 87 formed of rods extending between the branches 78 and 79. The ball is free to travel between the branches and will strike each branch in turn during oscillation to knock loose any ore which is stuck within the branch, particularly after a shut-down has allowed the ore to settle. Since the impact means will not generally be in use a stop 90 is affixed to the track to prevent movement of the ball within the track.

The interior of the shell may be heated in any suitable manner but in this embodiment an electric heating unit is provided within the interior of the shell proper. The heating unit 85 is preferably a removable unit which is heat insulated from the shell walls. Means are provided for preventing dust or residue within the shell from accumulating upon the heating element, by means of shields 69, which extend downward past the sides of the heating elements from the lower deck 55. The heating unit is supplied with current through a conductor cable 86. Transparent view ports, such as the glass port 83 are provided at appropriate locations in the walls of the shell in order to view the progress and condition of the ore. Thermometer wells are also located at various locations to indicate furnace temperatures at such locations.

A conductor tube 88 for the removal of volatile or gaseous constituents driven from the ore is connected at the top plate 25 of the shell 20. Means for condensing the volatile constituents, or gases, are provided in this embodiment by a counter flow cooling jacket 89 which surrounds the conductor tube 88 from a position proximate the gas outlet for a distance sufficient to cool the gases to condensation. The conductor tube 88 is preferably slightly sloped in the direction of flow to facilitate flow of the condensate by gravity, and extends to a swivel joint 91 of the type well known to the art which is substantially in alignment with the longitudinal axis of oscillation of the furnace. From the swivel joint 91 the conductor tube 88 is stationary and extends to a means for collecting the extracted constituents which are in liquid form after passing through the condensing jacket 89. If necessary to prevent a counterflow of air through the conductor tube 88 and into the furnace, the outlet end of the conductor tube is sealed from the atmosphere as, for example, by positioning the end of the tube 88 beneath the surface of water. A coolant inlet line 92 extends from a swivel joint 93 and is connected proximate the end of the cooling jacket 89. A coolant outlet line 94 is connected to the cooling jacket proximate the conductor 88 outlet connection to the shell 20 and extends to a swivel joint 95 which is again substantially aligned with the longitudinal axis of oscillation of the shell. For various treatments of ores or in other applications of a furnace in accordance with this invention, it is desirable to control the pressure within the shell. That is, in some instances it is desirable to heat the contents of the furnace under sub-atmospheric conditions while at other times a slightly pressurized condition is necessary. Means can therefore be provided at the conductor tube 88 for restricting the outward flow of the volatile constituents to create pressure within the shell 20, or to speed the flow in order to create a slightly sub-atmospheric condition in the furnace is desirable to facilitate volatilization of the mercury. Accordingly, the conductor tube 88 extends beyond the swivel joint 91 to a closed tank 96 containing water which partially fills the tank to a level above the open end of the conductor tube 88. A vacuum pump 97 is connected into the tank above the water level to maintain the tank at a partial vacuum. Thus, the condensed constituents flow from the conductor tube 88 and into the water and a partial vacuum is maintained in the conductor tube 88 and shell 20,

In operation, referring now to Figures 1 and 2, the heat of the furnace is raised to the required internal temperature by means of the heating unit 85 and the furnace is set in oscillation about the longitudinal axis extending through the shafts 28 and 29. Since the furnace shell 20 is also supported on the idlers 37 and 38 the weight of the furnace and its contents are not carried by the bearings 31 and 32 alone. Vertical movement of the bearings acts to compensate for expansion and contraction of the shell and maintains distribution of the weight among the four support points. Oscillation of the furnace is imparted by the prime mover through the crank 50 and driving rods 48 and 49. The rate of oscillation may be varied by varying the speed of the prime mover while the angle of oscillation may be varied by varying the radial location of the driving arm or arms upon the crank. When the furnace is set in oscillation the shell 20 and all parts appurtenant thereto are set in motion. That is, the ore outlet chute 62; the ore inlet tube, branches and arcuate trough; and the conductor tube 88, coolant jacket 89, and coolant inlet and outlet lines 92 and 94 will oscillate.

Ore is then fed to the stationary hopper 81 and fills the sleeve 82. Referring now to Figures 2 and 10, when the furnace approaches the extreme position of oscillation to the right side of the vertical for example, the branch 78 in Figures 2 and 10 will be in registration with the sleeve 82. Ore will then flow through the branch 78 to the ore inlet tube 75 by gravity. As the direction of oscillation reverses the sleeve 82 will be closed by the bottom plate of the arcuate trough 80 with which it is in sliding contact. As the opposite extreme of oscillation is approached the sleeve 82 moves into register with the second branch 79 and ore flows from the hopper 81 through the second branch 79 and to the ore inlet tube 75. In this position the first branch 78 is approximately horizontal. Thus, while one branch 79 is being partially emptied by flow of ore therefrom and being refilled from the sleeve 82, the opposite branch 78 is approximately horizontal and little or no flow of ore occurs through the opposite branch 78.

Raising or lowering of the ore plate 75 by means of the adjusting bolts 77 increases or retards the flow of ore from the ore inlet tube 75. That is, lateral openings are provided between the ore plate 76 and the open end of the ore inlet tube 75. As the ore inlet tube oscillates to one side of the vertical, the ore flows from the ore inlet tube and around the sides of the ore plate at the downward end of each side. Conversely, during oscillation of the furnace to the opposite side of the vertical, ore is allowed to flow from the opposite lateral opening of the ore plate. By raising or lowering the ore plate 76 with respect to the end of the inlet tube 75 the size of the lateral openings is varied to a position at which the rate of flow of ore from the inlet tube is such that ore is continually present in the inlet tube and both branches 78 and 79. The presence of the ore supplies a sealing means which prevents the ingress of air to the furnace and prevents the escape of gases and fumes from the furnace.

Thus, the ore is deposited at a controlled rate upon the first ore carrying deck 53 proximate the uppermost end thereof. As discussed hereinbefore, the longitudinal slope of the deck is insufficient to cause a sliding of the ore, however, as the deck oscillates the ore will slide transversely due to the oscillation with a longitudinal component due to the slope. Thus, the ore will follow a tortuous zig-zag path down the first deck 53 to the ore opening 57 at the lowermost end of the deck 53. The ore then drops onto the second deck 54 and travels in a similarly tortuous path in the opposite direction to the ore opening 57 of the second deck and then to the third deck 55. At the third deck the ore follows the tortuous

path to the lower end of the deck 55 and out of the shell 20 into the closed outlet chute 62.

During the slow flow of ore long this tortuous passage the ore is agitated and heating causing its volatile constituent, which is mercury in this illustrative embodiment, to be driven off and to flow to the outlet conductor tube 88. The heating of the ore is accomplished by the heating unit 85 and the circulation of heat is accomplished by circulation through the openings 58 in each deck. Similarly, the escape of volatile constituents from each deck as the ore progresses is accomplished by the flow of the fumes through the openings 58 to the upper plate of the shell. The volatile constituents then escape into the conductor tube 88.

Thus, the ore being treated is subjected to a series of agitated movements in a thin layer to obtain maximum heating and extraction efficiency while still maintaining a compact furnace. That is, the ore is constantly shifting, rolling, turning and changing position to absorb all heat possible during its movement. Since the absorption of heat is efficient, the heat supplied to the furnace is substantially completely extracted by the heat of vaporization imparted to the ore before the heated fumes and vaporized gases reach the conductor tube 88. Therefore, the heat supplied to the furnace need only be sufficient to maintain the volatile constituents in a vaporized condition as they enter the conductor tube 88. Accordingly, the cooling system required to condense the volatile constituents is less than that required by prior art devices since hot exhaust fumes and gases are substantially eliminated.

The ore or ore residue which has reached the ore outlet chute 62 flows downward therethrough and is restrained by the ore outlet plate as discussed hereinbefore. That is, the compressive force of the springs 71 is adjusted by means of the bolts 73 such that the ore is allowed to escape through the open sides of the plate at a rate which maintains ore in the outlet chute 62 at all times. As the ore outlet chute 62 oscillates ore tailings in excess of those retained in the chute for sealing off the chute 62 to the atmosphere escape from first one side and then the other side of the ore outlet plate 70, but at all times the chute is filled with ore to prevent the ingress of air to the shell or the escape of gases therefrom. As previously described the controlled entry of air or other gases may be provided through the valve 67.

As the volatile material passes through the conductor tube 88 it passes through the heat exchanger or cooling jacket 89 and is condensed to be recovered beyond the swivel joint 91 in liquid form. The maintenance of a slightly sub-atmospheric pressure at the conductor tube outlet will aid in the extraction of the gaseous constituents from the shell and will facilitate volatilization in the case of mercury extraction. As discussed hereinbefore, in this embodiment recovery of the mercury is achieved by exhausting the mercury which has been condensed in the tube into a quantity of water, the surface of which is maintained under a slight vacuum.

The cooling water is admitted to the cooling jacket 89 through the coolant inlet line 92 and out of the jacket through the outlet line 94.

Various modifications of the apparatus of the present invention, its arrangement of parts, and mode of operation will be apparent to one skilled in the art in view of the foregoing description. For example, in order to obtain maximum economy of space, when space is a consideration, the heating unit may be positioned between the lowermost deck and the deck above with suitable shielding to protect the elements from settling dust. That is, between the second and third decks in this embodiment. In such an arrangement it is preferable that the heat and fume openings 58 be positioned in the first and second decks substantially along the centerline of the shell at opposite ends of the decks and closed to the passage of ore by shields on all sides. Similarly, with

the openings 58 relocated, it is preferable for some applications to provide an ore opening 57 at both of the lower corners of each ore carrying deck above the lowermost deck. In an alternative embodiment of the present invention the shell and decks are of greater width than length to allow a greater movement of the ore in the direction of oscillation, and, in addition, the ore outlet chute is located to the side of the lowermost deck proximate the lower end of the deck, rather than on the longitudinal centerline as in the presently preferred embodiment. Further, similar modifications and uses of the present invention are possible within the scope of the invention.

Thus, the present invention provides an ore roasting furnace in which maximum heating efficiency is achieved in a substantially controlled atmosphere. A continuous regulated flow and agitation of ore through the furnace is possible without the ingress of air or escape of gaseous constituents from the furnace. The rate of flow of ore through the furnace is variable and may be closely controlled and predetermined for any particular application by use of the ore charging and outlet means of the present invention. In addition, the furnace contains a minimum of moving parts and parts subject to wear or abrasion with no moving parts within the heated chamber for maximum life and economy.

What is claimed is:

1. An ore roasting furnace for extracting the volatile constituents from ore comprising: a shell defining a heated ore chamber; means for heating said chamber; a plurality of ore carrying decks within said chamber and affixed thereto in stationary relationship, said decks being alternately longitudinally inclined to a first predetermined angle with respect to the horizontal axis of said shell, said predetermined angle being less than the angle at which said ore will move under the force of gravity; means for oscillating said shell to a second predetermined angle to each side of the vertical axis of said shell in the direction substantially transverse to said longitudinal direction, said second predetermined angle being greater than the angle at which said ore will move under the force of gravity; a hopper for feeding ore to said chamber, ore inlet means proximate the upper end of the uppermost of said decks, said ore inlet means including a tubular inlet to said chamber having an open end extending into the interior of said chamber, first and second divided inlet branches communicating with said tubular inlet exteriorly of said chamber in the plane of oscillation of said chamber, an arcuate trough connected between said divided branches, an ore outlet from said hopper extending into said trough and being closed thereby, said hopper ore outlet and said branches being alternately in registration at the limits of oscillation of said chamber, means for restraining the flow of ore through said tubular inlet so as to keep the inlet partially filled with ore to prevent the ingress of air to said chamber; ore outlet means proximate the lower end of the lowermost of said decks, means in combination with said ore outlet means to prevent the ingress of air to said chamber; ore openings through each of said decks above said lowermost deck proximate the lower end thereof; and outlet means from said chamber for said volatile constituents.

2. An ore roasting furnace for extracting the volatile constituents from ore comprising: a shell defining a

heated ore chamber; means for heating said chamber; a plurality of ore carrying decks within said chamber and affixed thereto in stationary relationship, said decks being alternately longitudinally inclined to a first predetermined angle with respect to the horizontal axis of said shell, said predetermined angle being less than the angle at which said ore will move under the force of gravity; means for oscillating said shell to a second predetermined angle to each side of the vertical axis of said shell in the direction substantially transverse to said longitudinal direction, said second predetermined angle being greater than the angle at which said ore will move under the force of gravity; a hopper for feeding ore to said chamber, ore inlet means proximate the upper end of the uppermost of said decks, said ore inlet means including a tubular inlet to said chamber having an open end extending into the interior of said chamber, first and second divided inlet branches communicating with said tubular inlet exteriorly of said chamber in the plane of oscillation of said chamber, an arcuate trough connected between said divided branches, an ore outlet from said hopper extending into said trough and being closed thereby, said hopper ore outlet and said branches being alternately in registration at the limits of oscillation of said chamber, means for restraining the flow of ore through said tubular inlet so as to keep the inlet partially filled with ore to prevent the ingress of air to said chamber; ore outlet means proximate the lower end of the lowermost of said decks, said ore outlet means including a tubular outlet communicating with the lowermost end of the lowermost ore carrying deck and extending to the exterior of said chamber for oscillation therewith, a resiliently mounted plate spaced beneath the outer open end of said tubular outlet, said plate being mounted such that a quantity of ore is maintained in said tubular outlet; ore openings through each of said decks above said lowermost deck proximate the lower end thereof; and outlet means from said chamber for said volatile constituents.

3. An ore roasting furnace for extracting the volatile constituents from ore comprising: a heated ore chamber, means for oscillating said chamber about the longitudinal axis thereof, ore inlet means affixed to said chamber for oscillation therewith, said ore inlet means comprising a tubular inlet to said chamber having an open end extending into said chamber at the top thereof, first and second divided inlet branches communicating with said tubular inlet in Y-configuration in the plane of oscillation of said chamber, an arcuate trough connected between said branches at the upper ends thereof, a stationary hopper for feeding ore to said ore inlet, a stationary ore outlet from said hopper extending into said trough and closed thereby, said ore outlet and said open branches being alternately in registration at the limits of oscillation of said chamber.
